T. L. VALERIUS.

BOTTLE CASE.

APPLICATION FILED MAY 13, 1905.

899,924.

Patented Sept. 29, 1908.

UNITED STATES PATENT OFFICE.

THEODORE L. VALERIUS, OF FORT ATKINSON, WISCONSIN, ASSIGNOR TO THE CREAMERY PACKAGE MFG. COMPANY, OF CHICAGO, ILLINOIS, A CORPORATION OF ILLINOIS.

BOTTLE-CASE.

No. 899,924.

Specification of Letters Patent.

Patented Sept. 29, 1908.

Application filed May 13, 1905. Serial No. 260,196.

To all whom it may concern:

Be it known that I, THEODORE L. VALERIUS, a citizen of the United States, and residing at Fort Atkinson, Jefferson county, 5 Wisconsin, have invented a certain new, useful, and Improved Bottle-Case, of which the following is a full, clear, and exact description, such as will enable others skilled in the art to which it appertains to make and use 10 the same.

My invention relates to bottle holding means or crates, and has special reference to improvements in portable bottle-cases or crates, such as are used by milkmen in transporting bottles of milk and cream.

The object of the invention is to provide a light, simple and durable case or crate for bottles and particularly for milk bottles, and the special object of the invention is to provide 20 a bottle case of such construction that bottles once placed therein may be readily secured and prevented from falling out when the case is inverted.

I attain these objects in a bottle case of 25 the construction and combination of the parts hereinafter described and particularly pointed out in the claims.

The invention briefly described, comprises 30 a bottle case or crate, chiefly characterized by movable bottle locking devices, which are permanent parts of the case and which being turned to one position permit bottles to be placed in or removed from the case, and being moved into another position, securely 35 lock or fasten all the bottles contained in the case.

My invention will be more readily understood by reference to accompanying drawing forming a part of this specification, and in 40 which:—

Figure 1 is a plan view of a bottle case embodying my invention; Fig. 2 is a vertical longitudinal section thereof on the line $x-x$ of Fig. 1. Fig. 3 is a transverse vertical section on the line $y-y$ of Fig. 1. Fig. 4 is an enlarged sectional view showing the manner of securing a bottle between two locking devices. Fig. 5 is an enlarged plan view of the locking end of one of the locking devices or 45 members; and, Fig. 6 is a detailed sectional view on the line $z-z$ of Fig. 5.

My bottle case as herein shown is, I believe of novel construction throughout, and while my invention is not limited to a bottle case

of the precise construction illustrated an understanding of the invention as a whole will be facilitated by a description of all of the details of its preferred embodiment. 55

In carrying out my invention I form the sides and ends, 2—2, and 3—3, from wide 60 boards. The side boards are preferably rabbed at the ends to join the end pieces 3, and the corners are strengthened by metal angle plate, 4. The open case thus formed is divided longitudinally by one or more low 65 partitions, 5, of about one-half the height of the case, and secured at their ends by nails driven through the end pieces, 3—3. For dividing the longitudinal spaces formed by the partitions within the case, I employ pairs 70 of tie rods, 6—6, which extend transversely across the case, piercing the partitions, 5—5, and having their ends secured in the side pieces 2—2.

I prefer that the ends of the rods 6—6, 75 shall be riveted over washers which are countersunk in the sides of the case as shown in Fig. 3. The riveting of the rods serves to bind the sides, 2—2, upon the ends 3 of the case. The partitions, 5, and pairs of rods, 80 6, together divide the lower part of the bottle case into a plurality of square bottle spaces, each adapted to receive a bottle, as indicated by dotted line in Fig. 3.

7—7, are bottle-supporting or bottom 85 rods. These are preferably of wood, and the lower portions of the sides, 2, and of the partitions, 5, are bored or perforated to receive them. After the rods 7 are inserted they are fastened by nails driven across the 90 holes in the vertical boards as shown in Figs. 2 and 3. The advantage of this construction is that the bottles are permitted to rest upon light, wooden parts which are sufficiently springy to obviate the breaking of 95 the bottles when a filled case is thrown or dropped on the floor.

I have here illustrated a bottle case that is adapted to contain twelve milk bottles, but it is obvious that my crate may be divided into any number of compartments by increasing or decreasing the number of partitions, 5, and pairs of rods, 6, with suitable complementary bottom rods, 7, one for each transverse row of bottle spaces. These bottle cases are intended to be piled one upon another and to prevent the breaking of bottles, I make the case of greater height than 100 105

the bottles, the tops of the latter being below the top of the case, as indicated in Fig. 3. It frequently happens that cases filled with bottles are inverted, either by accident or by intent, and to hold the bottles firmly in the case at such times, I equip the case with locking devices. These are preferably permanent, non-removable members contained within the case and adapted to engage the 10 necks and shoulders of all the bottles in the case. From a number of different embodiments of this portion of my invention, I have selected the locking device illustrated in the drawing as in every way best suited to the 15 purpose. This form of the device comprises a metal bar or light, narrow frame arranged within the case above the low partition therein and extending from end to end of the bottle case. It should be stated here that the 20 locking bars may be made of wood, but I prefer to employ metal and thereby avoid the annoyances attendant upon the expansion, contraction and warping of a wooden bar. Any suitable means may be employed for 25 securing the locking bar in operating position, so long as the means employed permit the bar to be operatively removed from the locking position to liberate the bottles and to open the case to receive bottles. The bar 30 may, if desired, be actually removable from the case, or it may be hinged at one end and secured by a suitable latch at the other. Objections may however, be urged against all 35 such constructions, and I have therefore chosen to make the locking devices actual permanent parts or members of the bottle case. I accomplish this by providing the 40 metal bar, 8, with convex edges, 9, and then pivoting the bar upon its longitudinal axis, arranging bosses or journals, 10, at the ends 45 of the bar for engagement with pivot screws, 12—12, provided in the ends, 3—3 of the case. It will be obvious that the bar thus pivoted may be turned into either a vertical 50 or a horizontal position. In the vertical position, see dotted lines Figs. 3 and 4, the bar is entirely within the planes of the sides of the underlying partition, 5, and in such position, does not interfere with the insertion 55 or removal of a bottle or bottles. In its horizontal position, the bar, 8, projects beyond the side planes of the partition, 5, and therefore overhangs the shoulders of the bottles in the compartments adjacent to said partition. The bases of the bottle necks are 60 curved and this permits the bar to be turned readily in either direction.

The dimensions of the bottle case, the compartments therein and of the bars correspond 65 to the dimensions of the bottles to be held in the case, and the construction is such that the locking bars quite firmly engage the necks of the bottles to prevent vertical movement thereof in the box or case. If desired, a locking bar or movable device may be pro-

vided upon each side, 2, of the case, but instead thereof I use small downwardly extending side springs, 2^a, to engage the bottles of the outer rows, and, aided by these, I find that two bars are sufficient to secure all of the 70 twelve bottles contained in the case. These springs hold the outer bottles upright when the case is inverted. It will be obvious that the bottles will be freed when the bars are turned or swung into their vertical position, 75 and to prevent the accidental freeing of the bottles in this manner, each locking bar is provided with a latch, as shown in Figs. 1, 4 and 5. The bar or elongated locking frame, 8, is provided with two holes at the end to 80 admit the ends of the forked latch, 13. This latch has a stem, 13', slidably held in one of the cross portions or bars, 8', and a spring, 14 arranged between the fork and the part, 8', thrusts the latch outward. Locking bar, 8, 85 is usually made of malleable iron, and the portion, 8', is provided with lips or lugs, 8''. The stem 13', of the latch fork is placed in the notch in the cross portion 8' after the ends of the fork have been thrust through the holes 90 in the end of the bar, 8; the lips, 8'', are then peened or turned over the stem, 13', to retain the same in the cross portion, 8', as shown in Fig. 5. By this construction I am 95 able to avoid making the latch in two parts. The movement of the latch in the bar, 8, is limited by stop lugs, 15 and 16 upon the latch and the bar, respectively. On the end, 3, of the case is a metal plate, 11, containing 100 holes corresponding to the locked position of the latch, and when the bar is turned to the horizontal position, the ends of the fork spring outward into the holes in the end of the case, thereby firmly securing the locking bar against rotation. The outward movement of the latch is preferably limited by 105 shoulders, 13'', upon the fork (see Fig. 5). It will be obvious that the latch may be readily withdrawn and that when the same is disengaged from the end of the case, the locking 110 bar may be rotated to the vertical position to open the bottle compartments. The case is preferably provided with hand-holes, 17, in its sides and ends, (see Figs. 2 and 3).

As it is obvious that numerous modifications of my invention will readily suggest themselves to one skilled in the art, I do not confine my invention to the specific constructions herein shown and described.

Having thus described my invention, I 120 claim as new, and desire to secure by Letters Patent:—

1. A bottle case, comprising sides and ends, in combination with parts dividing the lower part of the inclosure thus formed into 125 a plurality of compartments, a rockable bottle locking bar trunnioned in said case above said compartments, parallel with a row thereof and adapted in one position to lock the bottles in said case, and a bar latch for secur- 130

ing the bar in locked position, substantially as described.

2. A bottle case, containing a plurality of bottle compartments, in combination with an oblong bottle holding bar having convex edges and pivoted upon its longitudinal axis, and a latch for securing said bar in locked position, substantially as described.

3. A bottle locking device for bottle cases, comprising an elongated metal bottle holding bar or frame, having cross portions, in combination with a slideable latch having one end held in the end of said bar or frame, and malleable portions upon one of said cross portions for holding the other end of said latch, substantially as described.

4. A bottle case, comprising sides and ends, in combination with low partitions extending between said ends, bottom rods extending through said sides and said partitions, and tie-rods also extending through said sides and ends and with said partitions, dividing the space within said sides and ends into a plurality of compartments for bottles, and longitudinal rockable bottle-holding

bars above said partitions, substantially as described.

5. A bottle case, comprising suitable sides, ends and bottoms, with partitions, in combination with flat springs upon said sides to engage the bottles of the outer rows in said case, and rotary locking bars arranged in said case to engage the necks of bottles of adjacent rows, substantially as described.

6. A bottle case, comprising suitable sides and ends, in combination with a longitudinal partition, a series of transverse bottle-supporting rods, a bottle locking bar rotatably arranged in the upper part of the case upon its longitudinal axis, said bar being wider than said partition, and a slideable latch carried by said locking bar for securing the same in locked position.

In testimony whereof, I have hereunto set my hand, in the presence of two subscribing witnesses.

THEODORE L. VALERIUS.
